J. D. GOODWIN,
SAFETY RAZOR,
APPLICATION FILED MAY 28, 1919.

1,327,547.

Patented Jan. 6, 1920.

UNITED STATES PATENT OFFICE.

JAMES D. GOODWIN, OF RICHMOND, VIRGINIA, ASSIGNOR OF ONE-HALF TO WILLIAM K. DENNIS.

SAFETY-RAZOR.

1,327,547.

Specification of Letters Patent.

Patented Jan. 6, 1920.

Application filed May 28, 1919. Serial No. 300,264.

To all whom it may concern:

Be it known that I, JAMES D. GOODWIN, citizen of the United States, residing at Richmond, in the State of Virginia, have invented certain new and useful Improvements in Safety-Razors, of which the following is a specification.

This invention relates to an improvement in safety-razors of that type wherein the handle is adjustable with relation to the holder to arrange the blade in different angular relations to the handle for convenience in use.

The present invention provides means whereby the handle considered as a whole, is swiveled with relation to the blade holder to provide desired relative adjustments, with such handle and blade holder provided with coöperating locking means to fix such parts in positions of relative adjustment, the handle being made of separate sections, one comparatively short section having swiveled connection with the blade holder, and the other, constituting the main length wholly separable from the shaft section to permit the close storage demanded of articles of this type when in a case or not in use.

The invention further provides for utilizing the locking member for the adjustments of the blade holder and handle as a means for removably connecting the handle sections.

In the drawings:

Figure 1 is a perspective view of the improved safety-razor.

Fig. 2 is a view in elevation of the same, showing the blade holder adjusted to a position permitting the use of the implement practically as an ordinary razor.

Fig. 2^a is a similar view illustrating another adjustment of the blade holder.

Fig. 3 is a broken vertical section, showing the swiveled connection between the holder and handle, and the locking means for such swiveled connection.

Fig. 4 is a plan of the guard plate.

Fig. 5 is a longitudinal section of the clamping plate.

Fig. 6 is a detail transverse section.

Fig. 7 is a longitudinal section through the holder, the blade being shown in position.

The improved safety-razor is here shown as comprising a blade holder 1 and handle

section 2. The blade holder comprises a 55 guard plate 3, having slight, preferably rectangular projections 4 on the upper surface adjacent each end edge to fit end notches 4' in the blade A. At one end, the guard plate has an offset 5 formed with a 60 transverse slot 6, to receive one end of a co-operating lip 7 projecting from one end edge of a comparatively narrow clamping plate 8. The plate 8 is concavo-convex in cross-section, and the lip 7 is so arranged relative to 65 the bearing edges 9 of such plate, that when the plate 8 is forced down onto the blade A, the lip is put under tension. The clamping plate, at the end opposite the lip 7 is formed with a depression 10, having a flat bottom 70 wall 11, and securing member 12 is secured to the guard plate 3 to coöperate therewith. This securing member comprises a strip 13 slidably mounted on the relatively under surface of the guard plate, as by lips 14, 75 the outer end of the strip having an upstanding wall 15 terminating in an inturned lip 16, adapted when the clamping plate is in position to engage in the depression 10, bearing squarely on the bottom wall 11 thereof, 80 to hold the parts in fixed relation.

The strip 13 has a depending finger projection 17 whereby the securing member may be operated, and, incident to the tension of the lip 7 when the parts are in clamping 85 relation, release movement of the securing member results in the clamping member springing free of the clamping position, to facilitate removal of the blade.

The adjustable connection between the 90 handle and blade holder, comprises a substantially semi-spherical head 18 secured to and depending from the lower surface of the guard plate, having a plain upper portion which is arranged in spaced relation 95 to said guard plate. A ring 19, hereinafter termed a swiveled member is arranged between the head 18 and the guard plate, being rotatably mounted on the connection between said head and plate. The swivel member 100 has diametrically-opposed depending ears 20, projecting in close relation to the surface of the head.

The handle member is made up of two sections, one, termed a connecting section, 105 as 21, and the other, the handle proper, as 22. The connecting section 21, comprises a comparatively short section 23, having a

longitudinal threaded bore 24, with divergent arms 25 which are connected at their upper ends, the arms being pivotally connected, as by removable rivets 26, with the ears 20 of the swivel members.

The connecting handle section 21 is thus swiveled about the head 18, and may be arranged at substantially any angle with relation thereto. Furthermore the handle section 10 is short, and by reason of this fact such section projects but a short distance beyond the holder, it can therefore be conveniently packed in the usual case.

The handle proper comprises the usual hand-hold section 27, which may be of any desired form or convenient length from the upper end of which extends a screw 28, of a size to engage the bore 24 of the connecting handle section 21.

20 The head 18 and terminal of the screw 28 are formed for coöperation, so that by such coöperation the handle and blade holder may be secured in any position of adjustment permitted by the swiveled connection.

25 Such relative formation is here shown as a series of openings or depressions 29 in the head, the terminal of the screw 30 being formed to coöperate therewith. Other forms of such coöperation are contemplated.

30 The handle proper 22, may be unscrewed from the section 21 a sufficient distance to interrupt the coaction between the head 18 and the screw 28, and the blade holder and handle adjusted as desired, whereupon a 35 locking of such adjusted relation is secured by again severing the handle proper to cause the coöperation between the screw and head.

35 The handle proper is of course entirely separable from the connection section 21, so that in packing such handle, otherwise, an awkward extension from the blade holder, may be conveniently taken care of in the case.

Claims:

1. A safety razor comprising a blade holder, a two-part handle, one part of such handle having swiveled connection with the blade holder and formed with a threaded opening, the other part of such handle being wholly separable and provided with a threaded extension to engage the threaded opening and coöperating with the blade holder when in handle forming position to engage the swivel and lock said swivel movement. 50

2. A safety razor comprising a blade holder, a two-part handle, one part of such handle having swiveled connection with the blade holder, the other part of such handle 60 being wholly separable, and a connection between the two members of the two part handle to secure same together and coöperating with the blade holder when in handle forming position to lock said swivel movement. 65

3. A safety razor comprising a blade holder including a guard plate formed near one end with a slot and an adjacent raised portion, said blade holder having lips struck therefrom and bent to form parallel guides, a sliding plate formed with a slot through which the lips pass, the outer end of the sliding plate extending upwardly and laterally parallel with the blade holder to form 70 a tongue, a blade having a notch to engage the raised portion, a clamping plate concave-convex in cross section and formed at one end with an angular lip which engages in the slot, and disposed to place the clamping 80 plate under tension when in clamping position and formed at its opposite end with a depression the bottom of which is flat and with which the tongue engages, and a handle 85 extending from the blade holder. 75

In testimony whereof I affix my signature.

JAMES D. GOODWIN.
